[57] CLAIM

The ornamental design for a slip-on heat sink for long integrated-circuit modules, substantially as shown and described.

DESCRIPTION

FIG. 1 is an enlarged perspective view of a slip-on heat sink for long integrated circuit module showing my new design, the module being shown in broken lines for illustrative purposes only;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof;

FIG. 7 is a left side elevational view thereof.
